[57] CLAIM

The ornamental design for a combined latch and deadbolt unit, substantially as shown and described.

DESCRIPTION

FIG. 1 is a left side elevational view of combined latch and deadbolt unit embodying the new design, the outline depiction of a door being for illustrative purposes only;

FIG. 2 is an inside front elevational view thereof; FIG. 3 is a right side elevational view thereof, the outline depiction of a door being for illustrative purposes only;

FIG. 4 is an outside front elevational view thereof; FIG. 5 is a top plan view thereof, the outline depiction of a door being for illustrative purposes only;

FIG. 6 is a bottom plan view thereof, the outline depiction of a door being for illustrative purposes only; FIG. 7 is an inside rear elevational view thereof, the outside rear elevational view being a mirror image thereof;

FIG. 8 is an enlarged sectional view taken in the direction of the arrows on line 8—8 of FIG. 2; and

FIG. 9 is an inside front elevational view of a second embodiment of the design of FIG. 1, the only difference being the alternate handle configuration.
